(57) CLAIM

The ornamental design for a pendant, as shown and described.

DESCRIPTION

FIG. 1 is a view of the pendant of the present invention shown in use;

FIG. 2 is a front view thereof;

FIG. 3 is a rear view thereof;

FIG. 4 is a top view thereof;

FIG. 5 is a bottom view thereof;

FIG. 6 is side view thereof, as viewed from the right-hand side thereof; and,

FIG. 7 is a side view thereof, as viewed from the left-hand side thereof.

The broken line showing of a person and chain affixed to the pendant of the present invention in FIG. 1 is for illustrative purposes only and form no part of the claimed design.
